UNITED STATES PATENT OFFICE.

DOUGLAS BREWS, OF CLEVELAND, OHIO.

STEAM-WHISTLE.

1,313,251.

Specification of Letters Patent. Patented Aug. 19, 1919.

Application filed August 28, 1915. Serial No. 47,747.

To all whom it may concern:

Be it known that I, DOUGLAS BREWS, a citizen of the United States, residing at Cleveland, in the county of Cuyahoga and State 5 of Ohio, have invented certain new and useful Improvements in Steam - Whistles, of which the following is a specification.

This invention pertains to an improvement in steam whistles adapted more especially for 10 use on steam driven vessels, but not limited thereto, all substantially as shown and described and particularly pointed out in the claim.

In the accompanying drawings, Figure 1 15 is a side elevation of a boat or vessel on which the invention is installed, and Fig. 2 is a side elevation, more or less diagrammatic, of the invention apart from the vessel. Fig. 3 is an enlarged sectional elevation of the plunger and cylinder therefor through which the whistle proper is operated, as hereinafter fully set forth.

The modern steam propelled vessel has grown to be of what may be termed such 25 extreme length as compared with vessels built a decade or more ago, that the old installation which employed a wire running from the front of the vessel to the rear for the purpose of operating the steam whistle 30 is no longer regarded as either reliable nor desirable, owing chiefly, to the ineffectiveness of wire as a positive operating medium in vessels of the present length and type.

To these ends the present invention is developed on strictly fluid actuating lines and 35 comprises a whistle W at one end of the vessel and adapted to be blown by steam issuing through pipe 2 from the boiler or other source of supply and having a balanced valve of common structure in the casing 3 and which is provided with a stem 4 controlled by a lever 5 pivotally mounted 40 on said casing and adapted, when actuated, to press against said valve stem and open 45 said valve. Otherwise the valve is closed by the usual spring behind the same.

The lever 5 is operated by a link 6 and an evener 7 having a bifurcated or yoke shaped portion engaged by the hangers 8 50 pivotally suspended from the top of the plunger or piston 9 working in the cylinder 10. The said plunger is adapted to reciprocate in said cylinder sufficiently to operate the said valve through the mechanism just 55 described, and a fluid supply pipe 12 connects

with the bottom of said cylinder 10 and is in open fluid actuating connection from the front of the boat to operate said plunger and the valve actuating mechanism as described.

Means are provided at the front of the 60 boat to control the said plunger or piston 9 and the said valve, consisting in hand controlled pumps P and P' in open communication with the said pipe 12 and adapted to be placed in such position on the bridge and 65 in the cabin, respectively, as convenience may suggest. A water or liquid reservoir or tank 15 serves as a water supply for the system and is intended to be kept more or less completely filled and has a cap with a vent 70 for escape of air. A check valve 16 is provided in the pipe which connects said tank with the said pumps so that water can flow past said valve into said pumps but cannot be forced back into the tank, thus keeping 75 said pumps and the pipes therefrom to the cylinder 10 full of water. I mention water as the liquid commonly employed, but oil or any other practically inelastic fluid can be substituted.

At 20 I show a pump having pipe connections 18 and 19 through which the supply of liquid in the system can be replenished, and a globe valve 21 is preferably employed in the pipe 19 which leads from 80 pump 20 to the tank 15 to control the supply through said pipe 19.

The fluid in the several pipes being solid, in a sense, or inelastic, the operation of either of the two pumps P or P' will be instantly communicated through the pipe 12 to the plunger 9 and cause the said plunger to rise in proportion to the stroke of the pump which, in any event, is presumed to be sufficient to open the whistle valve and cause 90 the whistle to blow. Pipe 12 is open to both the pumps P and P' through the pipes 24 and 25 connected therewith respectively.

The plunger 9 has a small vent passage m through the same lengthwise which is 100 closed by a plug n at the top.

Suitable mechanical proportions are supposed to be observed throughout the system keeping in view the work to be done and the comparatively long distances between the 105 parts at the respective ends of the vessel. However, I have found that a half inch pipe 12 is large enough for distance service, and a three-fourths inch plunger. So it will be seen that an effective installation can be 110

made at comparatively small expense and with assured operation.

What I claim is:

A signaling device and means to operate 5 the same comprising a fluid actuated plunger having an exposed end and a hanger engaged with said end, an evener having said hanger engaged with one end thereof

and means at the other end of said evener operatively connected with said device. 10

In testimony whereof I affix my signature in presence of two witnesses.

DOUGLAS BREWS.
